UNITED STATES PATENT OFFICE.

WALTER D. YOUNG, OF BALTIMORE, MARYLAND.

CONTACT-SHOE FOR ELECTRIC RAILWAYS.

SPECIFICATION forming part of Letters Patent No. 738,649, dated September 8, 1903.

Application filed January 21, 1903. Serial No. 139,981. (No model.)

To all whom it may concern:

Be it known that I, WALTER D. YOUNG, residing in Baltimore city, in the State of Maryland, have invented a new and Improved 5 Contact-Shoe for Electric Railways, of which the following is a specification.

This invention relates to improvements in that type of contact or trolley shoe mechanisms more particularly adapted for use in 10 third-rail and sectional-conductor systems in which the third rail is disposed adjacent to and parallel with the regular trackways; and the said invention seeks to provide a current-pick-up mechanism of the character 15 stated embodying a simple but stable construction that will positively operate and make the desired contact in a manner such as will absolutely prevent any danger of the contact between the shoe and the rail being 20 broken.

My invention in its generic nature comprehends a novel construction of contact-shoe, including a hanger or supporting frame, and a means co-operatively connected therewith for sustaining it from the truck-frame in such manner as to permit a free lateral 25 vertically and longitudinally rockable action of the shoe or contacting member, whereby to accommodate the said shoe to the different 30 irregularities of the rail and without danger of breaking the current or rocking.

In its more complete nature my invention includes certain special features of construction especially designed for maintaining a 35 perfect insulation of the several current-conveying parts from the supporting means and to provide for carrying a current of very high amperage.

In its more subordinate features my invention consists in certain details of construction and peculiar combination of parts, all 40 of which will hereinafter be fully explained, and specifically pointed out in the appended claims, reference being had to the accompanying drawings, in which—

Figure 1 is a side elevation of my contact-shoe mechanism and illustrates the correlation of the same with the truck-frame to which it is attached. Fig. 2 is an end elevation 45 thereof. Fig. 3 is a plan view of the same. Fig. 4 is a vertical cross-section taken practically on the line 4-4 of Fig. 1. Fig. 5 is a

detail view of the wear-plate or shoe-carrying frame.

In its practical construction my invention 55 embodies an insulator head-block B, from which is pendently supported a holder A, that carries the contact-shoe, and the said block is supported on the main frame C and held thereon for vertical movement for a purpose presently explained.

In the practical adjustment of the several parts the upper end of the head-block B is projected under the laterally-extending pendent flange d, which extends entirely around 65 the sides and end of the block B and which is an integral part of the hanger-casting D, and the said flange d has for its purpose to shed the water from the block B and to act as a guide for the upper end of the said block, 70 as shown. The casting D is pendently supported under the cross member c of the main frame C, and it is held in a proper position relatively to the said frame C by the bolt or spindle E, that rises centrally from the casting D and which has a bearing in the aperture c' in the cross member c and is held for vertical movement in the long bearing c² in the vertical portion c³ of the main frame C. The upper end of the spindle E terminates in 80 a threaded tap e and is adapted to receive a stop-nut e², which limits the drop movement of the casting D and the several parts pendently supported therefrom. The casting D is held from rocking in a horizontal 85 plane and maintained in a fixed longitudinal position relatively to the frame C by guide-bolts d⁵, one of which extends upwardly from each end of the casting, and the said bolts pass through guide-apertures c⁴ in the cross 90 member c of the frame C, as clearly shown in Fig. 1.

F designates a buffer-spring disposed around the lower end of the spindle E between the top part of the casting D and the cross member c of the frame C, and to prevent the head-block, with the pendent shoe-supporting hanger portions, from dropping too low sleeves d⁶ are fitted on the upper projected ends of the rods d⁵, (see Fig. 4,) with which the washer 95 d⁷ and the nuts d⁸ coact, as shown. The cross member c is integrally formed with the frame C having laterally-projecting portions C⁶ C⁶ at the upper and lower ends held to straddle

the bumper H, and the said extensions are apertured to receive the bumper-bolt I, which bolt is insulated from the frame C by the insulated washers h and the sleeves h'. To hold 5 the frame C and the parts carried thereby in a proper longitudinal plane with the bumper-bolt, the said frame is firmly braced through the medium of the truss-rod J, one end of which is made fast to the journal-box casting 10 of the adjacent truck-wheel and its outer end secured by the adjustable eyebolt j to the cross member c of the frame C, as best shown in Figs. 1 and 3.

The head-block B is provided at each end 15 with a pair of vertical apertures b b, the upper portions of which are enlarged to form sockets b' b' to receive the heads of the hanger-bolts 10 10, that carry the shoe-holding frame A, which frame is U-shaped in cross-section 20 and is securely clamped on and to move with the head-block by the lock and jam nuts 10a 10a. The head-block B is also provided with an additional set of apertures b² b², the lower portions of which are enlarged to form sockets b³ to receive the heads of the hanger-bolts 25 12 12, that support the head-block from the casting-frame D.

By combining the frames D and A and the head-block B and coöperatively arranging 30 them in the manner described and shown a simple but stable construction of the several parts is effected and a perfect insulation of the hanger or contact-shoe-holding frame from the main frame is provided, and, furthermore, by joining the head-block B with the 35 frame A and the casting D by hanger-bolts 10 and 12, as shown, a free vertical play of the frame and the block B independent of the casting D is provided for, and in the event 40 the lift of the frame A and block B is excessive a limited free vertical movement of the casting D with the block B is provided for, the casting D acting as a buffer by reason of the position of the spring F around its central spindle, as shown.

The pendent portion of the U-shaped supporting-frame A terminates at the opposite ends in apertured ears a⁵ a⁵, through each set of which passes a cross-bolt M, the ends of 50 which have a loose or oscillatory movement in the elongated apertures a⁶ a⁶ in the ears a⁵ a⁵, the reason for which will presently appear. The cross-bolts M also pass through the longitudinally-extended flanges n n of the casting N, and the said bolts form the 55 supporting means for the casting N, and to join the casting N with the bolts M, so as to cause the two members M and N to swing in unison, each flange n n is formed with oppositely-projecting hubs n' n', whereby to produce long bearings for the bolts M, and also seat portions n² to receive the inner ends of the stout coil-springs O O, carried upon the bolts and having their outer ends engage 60 washers m⁵, which abut the inner faces of the ears a⁵ a⁵, as clearly shown in Fig 4.

The casting N is formed with laterally-pro-

jecting horizontal portions N² to oppose similar portions p² on a hanger-frame P, which is made fast to the flanges N² by the nuts and 70 bolts p³. The hanger at the lower end carries a horizontal longitudinally-extended plate p⁴, the ends of which are beveled to engage the undercut edges r of the contact or rubbing shoe R. The shoe R is made fast to 75 the plate p⁴ by the upwardly-tapering rivets p⁵, as clearly shown in Fig. 1, from which it will be apparent that by reason of the tapering rivets the wear on the shoe will tend to maintain a rigid connection between the shoe 80 and the plate p⁴.

From the foregoing description, taken in connection with the accompanying drawings, it is thought that the complete construction and the manner in which my invention operates will be readily understood by those skilled in the art to which it appertains.

It will be noticed that the means for sustaining the shoe provides a stable and strong construction of parts capable of transmitting current of excessively-high amperage with little or no leakage. Furthermore, ample means is provided for permitting the shoe to rise vertically to suit the vertical inclines and irregularities of the conductor-rail. The 95 shoe-hanger by reason of the manner in which it is connected to the head-block B and the peculiar support of the casting N in the U-shaped hanger A will rock freely in a longitudinal direction without affecting the head-block, the casting D, or the holder A. Furthermore, by reason of the manner in which the casting D is supported, the shoe-carrying portions are so hung that they will move laterally to accommodate the curves or lateral irregularities of the conductor-rail, and by reason of the buffer-springs O a uniform side pressure on the frame N and the shoe-hanger will be maintained, so as to hold the shoe to properly engage and contact with the conductor-rail when in its different lateral positions. The several parts are so combined and detachably connected that should one portion thereof wear or become broken it can be readily replaced without disarranging the 115 entire structure.

While the special construction of parts disclosed in the accompanying drawings shows a preferred construction, yet I desire it understood that I do not limit myself to the exact 120 details of construction shown, as they may be varied or modified without departing from the principle of my invention or the scope of the appended claims.

Having thus described my invention, what 125 I claim, and desire to secure by Letters Patent, is—

1. A contact-shoe of the character described, comprising a main frame, a hanger-frame pendently supported on the main frame, said hanger-frame including a shoe-carrying portion rockable in a vertical plane, a shoe carried thereby, means for normally adjusting the hanger-frame to bring the con-

tacting face of the shoe into engagement with the conductor-rail.

2. A contact-shoe of the character described, comprising a main frame, a hanger-frame hung on said main frame and adapted for vertical motion thereon, said hanger-frame including a portion longitudinally rockable and laterally movable and means for forcing the contacting face of the shoe against the conductor-rail.

3. A current-collector, comprising in combination with the buffer-block, a main frame connected thereto, said frame including a vertically-extending portion, a hanger-frame supported on the main frame, and having vertical motion, means for normally holding the hanger-frame to its depressed position, and a shoe-carrying member supported in the hanger-frame for lateral movement and longitudinally-rocking motion, as set forth.

4. In a current-collector of the character described, the combination with the hanger-frame A, and means for supporting it from the car-body; of the frame N supported in the frame A, longitudinally rockable and laterally movable; a contact-shoe carried by the frame N, and means for sustaining the frame N with the contacting shoe in a depressed position, as set forth.

5. The combination with the head-block B, and means for supporting it from the car-body, and the U-shaped hanger A; of the cross-bolts M rockably mounted on the U-shaped frame A, the hanger-frame N mount-

ed on the bolts M, the springs O O, and the shoe-plate connected to the hanger-frame, substantially as shown and described.

6. In a current-collector as described, the main supporting-frame C, including the base portion c, the casting D, having a central and end guides slideable in the frame portion c, an insulated head-block suspended from the casting D, a hanger-frame suspended from the head-block, and a shoe-carrier mounted on the hanger for lateral movement and vertically-rocking motion, as set forth.

7. In a current-collector as described, the combination with the main frame C, said frame including a vertical portion having a central bearing extending its length, a casting having a spindle to fit the said central bearing, said spindle having vertical movement with the said bearing, a stop at the upper end of the spindle to limit the drop movement of the casting, a buffer-spring for forcing the casting down, an insulated head-block supported from the casting, a hanger-frame pendently supported on the head-block, and a shoe-carrying member supported on the hanger-frame, said shoe-carrying member having horizontal movement and adapted for a rocking motion on a vertical plane, all being arranged substantially as shown and for the purposes described.
